TELLTALE FOR AUTOMOBILE LIGHTS

Dwight Ruggles Perry Heaton, Chappaqua, N. Y.

Application May 29, 1933, Serial No. 673,568

9 Claims. (Cl. 177—311)

My invention relates to electric lighting systems for automobiles.

An important object of the invention is to provide a system of the above mentioned character, wherein a single indicator element or bulb is employed to indicate when any one of the several bulbs of the lighting system, when turned on, has failed to glow.

A further object of the invention is to provide 10 a system of the above mentioned character formed of few and simple parts, and which may be arranged in a highly compact manner.

Other objects and advantages of the invention will be apparent during the course of the following 15 description.

In the accompanying drawing forming a part 20 of this application and in which like numerals are employed to designate like parts throughout the same, the figure is a diagrammatic view of a system embodying my invention.

In the drawing wherein for the purpose of 25 illustration is shown a preferred embodiment of my invention, the numeral 5 designates the filaments of the left and right cowl light bulbs of the automobile, these bulb filaments being designated "LC" and "RC", respectively. One end of each filament is grounded at 6, while the opposite end of the filament is connected with a wire 7, connected with a coil or winding 8, arranged about 30 a core 9 of an electro-magnet. The opposite end of each coil or winding 8 is connected with a wire 10, connected with a stationary contact 11, as shown.

The numerals 12 and 13 designate the two 35 filaments of the left and right headlight bulbs, which are designated "LH" and "RH", respectively. Corresponding ends of each pair of filaments 12 and 13 are connected with a wire 14, grounded at 15. The opposite end of each filament 12 is connected with a wire 16, connected with a 40 winding or coil 17, and surrounding a core 18 of an electro-magnet. The opposite end of each winding 17 is connected with a wire 19, connected with a wire 21, which is connected with a 45 stationary contact 22. Each filament 13 has its opposite end connected with a wire 23, connected with a coil or winding 24 of an electro-magnet, which coil or winding surrounds a core 25. The opposite end of each winding 24 is connected with a wire 26, connected with a 50 stationary contact 27.

The numeral 28 designates a filament included in a tail light bulb, and the filament 28 has one end connected with a wire 29, and this wire 29 is connected with a winding or coil 30, surround-

ing a core 31. The opposite end of the winding 30 is connected at 32 with a wire 33, extending in one direction for electrical connection with a stationary contact segment 34.

The numeral 35 designates the filament of a 5 stop light bulb, also designated "S". One end of this filament is connected with a wire 36, which is connected to a winding or coil 37, and this winding 37 is connected at 38 with a wire 40, which is connected with a stationary contact 41. Electrically 10 connected with the wire 40 at 38 is a winding or coil 42, and windings or coils 37 and 42 surround a core 43 of an electro-magnet. Windings 37 and 42 have their polarity arranged in opposition, so that when both windings 37 and 42 are energized, their 15 magnetism is neutralized. The winding 42 has one end connected with a resistance element 44, connected with a wire 45, grounded at 46. The opposite end of the filament 35 is connected with wire 45, as shown at 47. Wire 45 is connected 20 with one pole of the source of current 48, the opposite pole of which is connected with a wire 49, which is connected at 50 with a wire 51, and connected with a swinging contact 52, to engage stationary contact 41. The swinging contact 52 is to 25 be actuated by the movement of the brake pedal and will engage contact 41 when the brake pedal is depressed and will disengage the contact 41 when the brake pedal is released. Wire 49 extends beyond point 50 and is connected at 53 with a 30 double-ended swinging contact 54, included in a selective switch. As soon as one end of contact 54 is brought into engagement with contact 11, its opposite end will engage the contact segment 34, and will remain in engagement with this contact segment while the opposite end of contact 35 54 is swung from stationary contact 11 to stationary contact 22, for engaging contacts 11, 21, and 22.

Arranged near each set of electro-magnets is 40 a swinging armature 55, common to all magnets in the set. These armatures are connected with a wire 56, grounded at 57. Each armature 55 is adapted to engage with a stationary contact 58, connected with a wire 59, connected with a stationary contact 60. Contacts 60 normally engage contacts 61, which may be springs, included in a contact device 62. The contact device is connected with a wire 63 having one end of the filament 64 of the indicator bulb connected therewith, which indicator bulb is also designated "I". The filament 64 has its opposite end connected with wire 33.

A wire 65 is connected with wire 63, and is connected with a stationary contact 66, arranged 50 55

to be engaged by an armature 67, connected with a wire 68, also connected with the opposite end of the filament 28 of the tail light. Wire 68 is grounded at 69. Connected with the wire 63 is 5 a wire 70, connected with a stationary contact 71, adapted to be engaged by an armature 72, grounded at 73.

The operation of the system is as follows:

- The selective switch is operated by turning contact element 54 for lighting the selected bulb filaments. If it is desired to light the cowl bulb filaments, contact 64 will engage contact 11 and contact segment 34. With this adjustment, the 10 electro-magnet winding 8 in each set will be energized and the armature 55 will be held out of contact with stationary contact 58. Current will now flow from one pole of the source of current 48 through wire 49, contact 54, contact 11, each wire 10, each winding 8, each filament 5, and each ground 6, back to ground 46 and to the opposite pole of the source of current. The current 15 also passes from contact 54 through contact segment 34, wire 33, electro-magnet winding 30, tail light filament 28, wire 68, ground 69, and back to ground 46 of the source of current. Armature 67 is therefore held out of contact with contact 66, and armature 72 is also held out of contact with contact 71, since stop switch 52 is open. The indicator bulb filament therefore has 20 no closed circuit and will not glow. Assuming that the left cowl bulb filament 5 should burn out with this adjustment of parts, then all of the electro-magnet windings 8, 17, and 24 of the left set would be deenergized, and armature 55 comm- 25 on to these electro-magnets would drop and engage contact 58. When this occurs, a circuit will be closed to cause the indicator bulb filament 64 to glow, and in this closed circuit current will flow from one pole of the source of current 48 through wire 49, contact 54, contact segment 34, wire 33, indicator bulb 64, wire 63, contact 61, contact 60, wire 59, armature 55, wire 56, and back to the ground 46 of the source of current. The indicator bulb filament 64 will thus glow and 30 indicate that either the left or right cowl bulb filament 5 is burned out. The operator may shift the contact device 63 to the right to bring spring contact 61 out of engagement with contact 60 to the left, while spring contact 61 will engage 35 contact 60 to the right. When this is done, the indicator bulb filament 64 will cease to glow, and the operator will then know that the trouble is with the left cowl light. By swinging contact 54 until it engages contact 27, the left and right headlight bulb filaments 13 will be connected in the closed circuits, and will glow, and the indicator bulb filament 64 will glow when either of these filaments burn out, as is obvious. By bringing the contact 54 into engagement with contact 40 22, the head-light bulb filaments 12 will be connected in closed circuits and these filaments will glow and the indicator bulb filament 64 will glow when either of the filaments 12 burn out. The contact device 62 may be manipulated in the 45 manner described, for determining whether the trouble is with the left or right filaments 13, or with the left or right filaments 12. When the contact 54 engages either contact 11, 27 and 22, contact 54 engages contact segment 34 and the 50 tail light filament 28 is connected in a closed circuit and will glow. In this closed circuit, current will flow from the source of current 48 through wire 49, contact 54, contact segment 34, electro-magnet winding 30, wire 29, tail light filament 28, wire 68 and ground 69, back to the ground 46

of the source of current. The electro-magnet winding being energized, armature 67 is held out of contact with contact 66. When the tail light filament 28 burns out, armature winding 30 is deenergized and armature 67 automatically engages contact 66 and a circuit is closed to cause the indicator bulb filament 64 to glow. In this closed circuit, current will flow from one side of the source of current 48, wire 49, contact 54, contact segment 34, wire 33, indicator bulb filament 64, wire 63, wire 65, contact 66, armature 67, wire 68, and through ground 69 to the ground 46 of the source of current. When the brakes are applied, the contact 52 engages contact 41 and a circuit is closed to cause the stop light bulb 15 filament 35 to glow. In this closed circuit, current will flow from one side of the source of current 48 through wire 49, through wire 51, contact 52, contact 41, wire 40, electro-magnet winding 37, wire 36, stop light bulb filament 35, wire 45 20 and back to the opposite pole of the source of current. The current divides at 38 and also passes through the electro-magnet winding 42 and then through the resistance 44 and through the wire 45, back to the opposite pole of the 25 source of current. Since electro-magnet windings 37 and 48 have their polarity reversed or in opposition, and since they are of essentially the same strength, the magnetism of one is neutralized by the magnetism of the other, and armature 72 30 will not engage stationary contact 71. Now, when the stop light bulb filament 35 burns out with contact 52 engaging contact 41, electro-magnet winding 37 is deenergized, while electro-magnet winding 42 is energized and armature 72 35 will be drawn into engagement with contact 71, and a closed circuit is provided to cause the indicator bulb filament to glow. In this closed circuit, current will pass from one side of the source of current 48, through wire 49, contact 54, contact segment 34, wire 33, indicator bulb filament 64, wire 63, wire 70, contact 71, armature 72, ground 73 and through ground 46 back to the opposite pole of the source of current. 40

It is to be understood that the form of my invention herewith shown and described is to be taken as a preferred example of the same and that various changes in the size, shape, and arrangement of parts may be resorted to without departing from the spirit of my invention or the 45 scope of the subjoined claims. 50

I claim:

1. In a lighting system for automobiles, a source of current having one side grounded, a plurality of electric bulb filaments, an electro-magnet for each bulb filament having a winding connected with the source of current and such bulb filament, the bulb filaments and electro-magnets being arranged in a plurality of groups, an indicator bulb filament having one terminal connected with the ungrounded side of the source of current, a plurality of contacts connected with the opposite terminal of the indicator bulb filament, a grounded armature for each group of electro-magnets and arranged to engage the corresponding contact when all of such electro-magnets in its group are deenergized. 55
2. In a lighting system for automobiles, a source of current, a plurality of sets of electric filaments arranged near the opposite sides of the automobile, the corresponding filaments in the two sets constituting pairs, electro-magnetic means for the filaments in each set, each electro-magnetic means including a plurality of windings corresponding in number to the filaments in each set. 60

- each winding being connected with the corresponding filament in such set, a switch for selectively connecting the windings of the several pairs of filaments with the source of current, an indicator bulb having one terminal connected with one side of the source of current, a plurality of contacts connected with the opposite terminal of the indicator bulb, an armature for each contact, each armature being arranged near the electro-magnetic means for each set of filaments and electrically connected with the other side of the source of current, the arrangement being such that such armature is held from engagement with its corresponding contact when any one winding in its electro-magnetic means is energized.
3. In a lighting system for automobiles, a source of current, a plurality of sets of electric filaments, arranged near the opposite sides of the automobile, the corresponding filaments in the two sets constituting pairs, electro-magnetic means for the filaments in each set, each electro-magnetic means including a plurality of windings corresponding in number to the filaments in each set, each winding being connected with the corresponding filament in such set, a switch for selectively connecting the windings of the several pairs of filaments with the source of current, an indicator bulb having one terminal connected with one side of the source of current, a plurality of contacts connected with the opposite terminal of the indicator bulb, an armature for each contact, each armature being arranged near the electro-magnetic means for each set of filaments and electrically connected with the other side of the source of current, the arrangement being such that such armature is held from engagement with its corresponding contact when any one winding in its electro-magnetic means is energized, and means to selectively break the electrical connection between the first named contacts and the indicator bulb.
4. In a lighting system for automobiles, a source of current, a set of electric filaments, electro-magnetic means for the set of electric filaments and including a plurality of windings corresponding in number to the filaments in the set, each winding being connected with the corresponding filament in the set, an indicator bulb, means including a switch for connecting the windings of the several filaments and one terminal of the indicator bulb with one side of the source of current, a contact connected with the opposite terminal of the indicator bulb, an armature for the contact, the armature being arranged near the electro-magnetic means for the set of filaments and electrically connected with the one side of the source of current, the arrangement being such that the armature is held from engagement with its contact when any one winding in the electro-magnetic means is energized.
5. In a lighting system for automobiles, a source of current, a plurality of sets of electric filaments arranged near the opposite sides of the automobile, the corresponding filaments in the two sets constituting pairs, electro-magnetic means for the filaments in each set, each electro-magnetic means including a plurality of windings corresponding in number to the filaments in each set, each winding being connected with the corresponding filament in such set, a tail light, an electro-magnet having a winding connected with one terminal of the tail light, an indicator bulb, a switch for selectively connecting the windings of the several pairs of filaments, the winding of the electro-magnet, and one terminal of the indicator bulb with one side of the source of current, a plurality of contacts connected with the opposite terminal of the indicator bulb, an armature for each contact, each armature being arranged near the electro-magnetic means for each set of filaments and electrically connected with the other side of the source of current, the arrangement being such that such armature is held from engagement with its corresponding contact when any one winding in its electro-magnetic means is energized, a contact connected with the said opposite terminal of the indicator bulb, an armature arranged near said electro-magnet and electrically connected with such other side of the source of current and held from engagement with the last named contact when the electro-magnet is energized, and means to selectively break the electrical connection between the first named contacts and the indicator bulb.
6. In a light system for automobiles, a plurality of groups of lighting circuits, each circuit in each group including a bulb filament, electro-magnetic means for each group of lighting circuits and including windings corresponding in number with the bulb filaments in such group of circuits and connected with such bulb filaments, an armature to be moved by the electro-magnetic means of each group of circuits, an indicator circuit including a signal element, means controlled by the armatures for retaining the indicator circuit open at points when all electro-magnetic means are energized, the arrangement being such that each electro-magnetic means is energized when any one winding included therein is energized, a source of current, and means for connecting selected corresponding lighting circuits of the groups and the indicator circuit with the source of current.
7. In a lighting system for automobiles, a plurality of groups of lighting circuits, each circuit in each group including a bulb filament, electro-magnetic means for each group of lighting circuits and including windings corresponding in number with the bulb filaments in such group of circuits and connected with such bulb filaments, an indicator circuit including a signal element, an armature to be moved by the electro-magnetic means of each group of circuits, means controlled by the corresponding armature to close the indicator circuit by the action of any armature when its electro-magnetic means is deenergized, the arrangement being such that each electro-magnetic means is deenergized when all of the windings included therein are deenergized, a source of current, means for connecting the indicator circuit with the source of current, and means to connect selected light circuits of the groups with the source of current.
8. In a lighting system for automobiles, a plurality of groups of lighting circuits, each circuit in each group including a bulb filament, electro-magnetic means for each group of lighting circuits and including windings corresponding in number with the bulb filaments in such group of circuits and connected with such bulb filaments, an armature for the electro-magnetic means of each group of circuits, an indicator circuit including a signal element, means controlled by the armatures for retaining the indicator circuit open at points when all electro-magnetic means are energized, the arrangement being such that each electro-magnetic means is energized when any one winding included therein is energized.

- source of current, means for connecting selected corresponding lighting circuits of the groups and the indicator circuit with the source of current, a circuit connected in parallel with the indicator
- 5 bulb circuit and including a tail light bulb filament, and means to close the indicator bulb circuit when the bulb in the closed tail light circuit ceases to glow.
9. In a lighting system for automobiles, a
- 10 source of current, a plurality of electric bulb filaments which are arranged in groups, separate electro-magnetic means for each group of bulb filaments including windings connected with one side of the source of current and the terminals of
- 15 the bulb filaments, means for electrically con-

necting the opposite terminals of the bulb filaments in each group with the opposite side of the source of current, an indicator bulb, the filament of said indicator bulb having one terminal connected with one side of the source of current, 5 a plurality of contacts connected with the opposite terminal of the indicator bulb filament, a separate armature for each electro-magnetic means and arranged to engage the corresponding contact and electrically connected with the opposite 10 side of the source of current, the arrangement being such that each armature is held from engagement with its contact when any one winding of its electro-magnetic means is energized.

DWIGHT RUGGLES PERRY HEATON. 15
